DESIGN FOR A COVER FOR BOXES, CARTONS, OR THE LIKE

Jane Dow Cady, Newton, Mass.

Application February 20, 1933. Serial No. 47,266

Term of patent 3½ years

To all whom it may concern:

Be it known that I, JANE Dow CADY, a citizen of the United States, and a resident of Newton, county of Middlesex, and State of Massachusetts, have invented a new, original, and ornamental Design for a Cover for Boxes, Cartons, or the like, of which the following is a specification, reference being had to the accompanying drawing, forming part thereof.

The figure is a perspective view of a cover for boxes, cartons, or the like, showing my new design.

I claim.

The ornamental design for a cover for a box, carton, or the like as shown.

In witness whereof, I hereunto subscribe my name this 25th day of January, 1933.

JANE DOW CADY.
